CLAIM

The ornamental design for a combination rocket, toy chest, and rocking apparatus, as shown and described.

DESCRIPTION

FIG. 1 is a side perspective view of the combination rocket, toy chest, and rocking apparatus with the rocket cockpit shown from the latching side, according to my new design:

FIG. 2 is a perspective view of the combination rocket, toy chest, and rocking apparatus with the rocket cockpit shown from the hinged side, on the side opposite the latching side; FIG. 3 is a front perspective view of the combination rocket, toy chest, and rocking apparatus, showing a portion of the nose cone, steering wheel, and seat;

FIG. 4 is a rear perspective view of the combination rocket, toy chest, and rocking apparatus, showing the upper tail fin and spaced apart, lower rocking tail fins;

FIG. 5 is a side perspective view of the combination rocket, toy chest, and rocking apparatus with the upper housing portion raised above the lower housing portion to show the internal toy chest; and,

FIG. 6 is a perspective bottom view of the combination rocket, toy chest, and rocking apparatus standing upright on all three tail fins, for compact storage.
